Patented Apr. 4, 1916.

UNITED STATES PATENT OFFICE.

HYMAN STEIN, OF WABASH, INDIANA.

REMOVABLE SEWER CATCH-BASIN.

1,178,355.

Specification of Letters Patent.

Patented Apr. 4, 1916.

Application filed September 13, 1915. Serial No. 50,450.

To all whom it may concern:

Be it known that I, HYMAN STEIN, a citizen of the United States, residing at Wabash, in the county of Wabash and State of Indiana, have invented certain new and useful Improvements in Removable Sewer Catch-Basins; and I do declare the following to be a full, clear, and exact description of the invention, such as will enable others skilled in the art to which it appertains to make and use the same.

This invention relates to improvements in removable sewer catch basins.

The object of the invention is to provide a simply constructed device of this character which may be placed in and readily removed from any ordinary sewer catch basin such as are usually formed at intervals in sewers for receiving sediment and the like.

Another object is to provide a removable sewer catch basin equipped with means for preventing it from sticking or being held by suction in the stationary sewer basin in which it is disposed.

With the above and other objects in view, the invention consists of certain novel features of construction, combination and arrangement of parts which will be herein-after fully described and claimed.

In the accompanying drawings: Figure 1 represents a vertical section of a sewer with the stationary catch basin formed therein, equipped with this removable catch basin disposed in operative position therein;

Fig. 2 is an enlarged rear elevation of the removable catch basin removed; Fig. 3 is a central vertical section of the basin taken on the line 3—3 of Fig. 2 with the bottom shown in open position in dotted lines; Fig.

4 is a horizontal section taken on the line 4—4 of Fig. 2.

In the embodiment illustrated, a removable sewer catch basin or cleaning basket is shown rectangular in form to adapt it to a stationary catch basin B of this form, although obviously it may be of any other desired cross sectional contour according to the shape of the stationary basin in connection with which it is designed to be used.

This removable basin or basket comprises four corner uprights or standards 1 shown constructed of angle iron and having their upper ends connected by cross bars 2 which are also formed of angle iron having their

ends overlapping. Eye-bolts 3 extend through the overlapping ends of the cross bars 2 at the corners of the basket and thus perform the double function of additional securing means for connecting the cross bars and as means for connecting the chains 4 to the basket, said chains being designed to be used as handles for raising and lowering the basket and are here shown secured to a ring 5. This ring 5 is adapted to be engaged with a hook 6 of a hoisting apparatus which may be mounted on any suitable structure for raising and lowering the basket.

Side plates 7 are secured to the standards 1 with the lower ends of said standards extending below the bottom edges of said plates to form supporting feet 8 for the basket which are designed to rest on the bottom of the stationary basin B when applied as is shown clearly in Fig. 1. These plates 7 are of a height and are so disposed on the standard 1 that the upper edges thereof will be arranged substantially in alinement with the upper edges of the top walls of the basin B to which the basket is to be applied so that no sediment or other material which enters the basket will extend over the top of the plates 7 and drop down into the stationary basin. The standards 1 extend some distance above the top edges of the plates 7 and form a skeleton frame above said plates, which latter constitutes the body portion or sediment containing receptacle of the basin when taken in connection with the bottom 9 to be described.

As shown, a grating is formed at the discharge or outlet side of the basket, although obviously such a grating may be arranged on all sides of the basket except at the inlet thereof. This grating as shown, comprises a plurality of heavy wire rods 10 which have their ends bent laterally substantially at right angles and which are inserted through apertures in the upper edge of the rear plate 7 of the basket and in the depending flange 102 of the rear connecting cross bar 2 as is shown clearly in Figs. 1, 2 and 3. The ends of these rods 10 after they are inserted through the apertures in the plate and cross bar, are upset to form retaining heads 11, whereby they are reliably held in engagement with the parts to which they are applied. These bars 10 are spaced laterally

- apart any suitable or desired distance sufficient to prevent the passage between them of paper and similar trash and yet permit fluids to flow freely therebetween.
- 5 The bottom 9 is hinged at one side thereof to the lower edge of one of the plates 7, being here shown hingedly connected with the front plate and is designed to open downwardly as shown in dotted lines in Fig. 3.
- 10 This bottom 9 is retained in closed position by a spring catch 12 carried by one of the plates 7 and which may be tripped by any suitable means, not shown, to open the bottom 9 when desired for dumping the basket.
- 15 This bottom 9 has an opening 13 here shown arranged centrally therein and around which is formed an upstanding internally threaded collar 14 which is designed to receive the threaded lower end 15 of a
- 20 suction breaking pipe 16 which extends upwardly into the basket to a point beyond the normal water level in the sewer S in which this basket is designed to be mounted. While this pipe 16 is shown connected with
- 25 the bottom 9 by means of its threaded engagement with the collar 14, it is to be understood that it may be connected therewith by any other suitable means, it being preferably detachable to provide for its removal
- 30 when desired for cleaning or other purposes. This pipe 16 is designed to break the suction between the bottom 9 and the lower wall or bottom of the stationary basin B, permitting the air to enter under said bottom 9
- 35 and thus prevent the bottom from sticking or being held by a vacuum formed under the basket such as might be likely to occur on the removal of the basket were this pipe not provided.
- 40 In the use of this removable basin or cleaning basket, the bottom 9 having first been closed, the basket is lowered through a manhole M disposed above the stationary basin B in which the basket is to be mounted
- 45 and said basket is lowered through the manhole into said basin B until the feet 8 thereof engage the bottom of said basin, it being of course understood that the basket is so disposed that the grating formed by the bars
- 50 10 will be arranged at the outlet or discharge end of the sewer, while the unobstructed portion thereof will be arranged opposite the grating or toward that portion of the sewer through which the sewerage flows in
- 55 the direction of the arrow shown in Fig. 1. After this basket has been placed in the basin B, it is allowed to remain until the body portion formed by the plates 7 thereof becomes filled or nearly so and it is then re-
- 60 moved by engaging a hoisting apparatus with the ring 5 and thereby lifting the basket bodily with the contents thereof through the manhole M. After it has been raised from the sewer, this basket may be dumped either
- 65 into a wagon provided for this purpose or
- into any other suitable receptacle and the catches 12 may be actuated either manually or mechanically at the will of the operator, trips being preferably provided for this purpose so that the dumping of the basket will 70 become automatic. After the basket has been dumped and the bottom 9 again closed, it is lowered into the basin B through the manhole M and is again ready for use.
- It is of course to be understood that the sewer S is provided as usual, with a plurality of stationary basins B arranged at intervals and which are disposed below the manholes M which afford access thereto and by equipping each of these basins B with one of 80 these removable basins or baskets, great saving in time and labor is effected when cleaning out the sewer basins.
- This basket or removable basin while very simple in construction and thus adapted to 85 be cheaply manufactured, is strong and reliable in operation.
- I claim as my invention:
1. A removable sewer catch basin comprising a plurality of uprights, side plates 90 secured to said uprights, said uprights projecting above and below said plates forming standards above and feet below, cross bars connecting the upper ends of said standards, a grating arranged on the outlet side of said 95 basin between one of said cross bars and plates, a hinged drop bottom mounted on said basin, a catch for holding said bottom closed, and means for engagement by a hoisting device.
2. A removable sewer catch basin comprising angle iron uprights, angle bars connecting the upper ends of said uprights, side plates secured to said uprights and of a height substantially corresponding to the 100 depth of the stationary basin in connection with which it is designed to be used, said uprights extending below the bottom edges of said plates to form supporting feet, a downwardly opening bottom hinged at one edge to the lower edge of one of said plates, a catch on another of said plates for holding said bottom in closed position, wire rods engaged at their opposite ends with one of said plates and with one of said upright 105 connecting bars, the ends of said rods being bent laterally inward and extended through said plate and bar and upset to retain them in operative position, eye-bolts engaged with the flanges of said connecting bars, lifting chains engaged with said eye-bolts, and a ring connecting said chains.
3. A removable sewer catch basin having a downwardly opening bottom, and a suction breaking pipe opening through said bottom 110 and having its upper end so positioned as to dispose it in a plane above the normal water level of the sewer in connection with which said basin is to be used.
4. A removable sewer catch basin having 115
- 120
- 125
- 130

a downwardly opening bottom having an opening therein, a threaded collar surrounding said opening, and a pipe having threaded engagement with said collar and extending upwardly in said basin to a point above the normal water level of the sewer to which the basin is to be applied.

In testimony whereof I have hereunto set my hand in presence of two subscribing witnesses.

HYMAN STEIN.
